US00D560167S

(12) **United States Design Patent** (10) Patent No.: **US D560,167 S**
Malis et al. (45) Date of Patent: **** Jan. 22, 2008**

(54) **SURGICAL INSTRUMENT PLUG**

(75) Inventors: **Jerry L. Malis**, King of Prussia, PA (US); **Anthony John Groch**, Mantua, NJ (US); **Robert R. Acorey**, Cherry Hill, NJ (US)

(73) Assignee: **Synergetics USA, Inc.**, King of Prussia, PA (US)

(**) Term: **14 Years**

(21) Appl. No.: **29/277,892**

(22) Filed: **Mar. 13, 2007**

Related U.S. Application Data

(62) Division of application No. 29/246,472, filed on Apr. 17, 2006, now Pat. No. Des. 547,867.

(57) **CLAIM**

The ornamental design for a surgical instrument plug, as shown and described.

DESCRIPTION

FIG. 1 is a top perspective of a surgical instrument plug in accordance with our new design;

FIG. 2 is a right side elevational view of the plug shown in FIG. 1;

FIG. 3 is a left side elevational view of the plug shown in FIG. 1;

FIG. 4 is a front elevation view of the plug shown in FIG. 1;

FIG. 5 is a rear elevation view of the plug shown in FIG. 1;

FIG. 6 is a top plan view of the plug shown in FIG. 1; and,

FIG. 7 is a bottom plan view of the plug shown in FIG. 1.

The broken lines in the figures are for illustrative purposes only and form no part of the claimed design.
